United States Patent Office

Des. 183,031
Patented June 10, 1958

183,031

DESK TRAY

Franklin E. Tarte, Jr., Media, Pa.

Application June 19, 1956, Serial No. 41,973

Term of patent 7 years

(Cl. D74—1)

FIG. 1.

FIG. 4.

FIG.3.

FIG.2.

I claim:

The ornamental design for a desk tray, as shown.
